UNITED STATES PATENT OFFICE.

AUGUSTA Y. DARCHE, OF CHICAGO, ILLINOIS

DESIGN FOR A STAND FOR ELECTRIC ALARM-CLOCKS.

SPECIFICATION forming part of Design No. 37,091, dated August 16, 1904.

Application filed April 25, 1904. Serial No. 204,914. Term of patent 7 years.

To all whom it may concern:

Be it known that I, AUGUSTA Y. DARCHE, a citizen of the United States, residing at Chicago, in the county of Cook and State of Illinois, have invented a new, original, and ornamental Design for a Stand for Electric Alarm-Clocks, of which the following is a specification, reference being had to the accompanying drawings, forming part thereof.

Figure 1 is a front elevation, and Fig. 2 is a plan view, showing my new design.

What I claim is--

The ornamental design for a stand for electrical alarm-clocks, as shown.

AUGUSTA Y. DARCHE.

In presence of—

GERTRUDE L. NEFF,
SAMUEL J. LUMBARD.
